Primary Examiner — Wan Laymon

(57) **CLAIM**

The ornamental design for a dental model, as shown and described.

DESCRIPTION

FIG. 1 is a front, left side, top perspective view of a dental model showing my new design;

FIG. 2 is a rear, right side, bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a front, left side, top perspective view thereof when the model is open. The broken lines depict portions of the dental model that form no part of the claimed design.

1 Claim, 9 Drawing Sheets
